UNITED STATES PATENT OFFICE

2,234,365

STEAM LOCOMOTIVE DRIVEN BY HIGH SPEED PISTON STEAM ENGINES

Heinrich Carl, Kassel, Germany, assignor to
 Henschel & Sohn, Gesellschaft mit beschränkter
 Haftung, Kassel, Germany

Application November 26, 1938, Serial No. 242,462
 In Germany December 15, 1937

1 Claim. (Cl. 105—37)

Applications have been filed in Germany December 15, 1937 and April 1, 1938.

The invention relates to steam driven locomotives, more particularly locomotives designed for high running speeds, in which each individual driven axle is driven by a high speed piston steam engine mounted upon the sprung frame. The high number of revolutions of the steam engine necessitated by structural and economical requirements, has, in the hitherto known constructions of such individual axle drives, always been attained by the employment of toothed wheel transmission gears. The driven wheels used in these constructions have a fairly large diameter (about 1600 mm. and more). These known constructions have the following drawbacks:

In order to use for each axle the simplest possible toothed wheel transmission gear, that is a gear comprising only one pair of toothed wheels, it would be necessary to mount the driving engine between the wheels within the frame. This would render accessibility of the engine very difficult owing to the boiler being superposed over the engine, and consequently it would be very difficult to watch the operation of the engine. Moreover, it would be very difficult and expensive to dismount the engine for the purpose of a thorough inspection or repairs, as it would be necessary to dismount with the engine the whole set of wheels and the toothed wheel transmission.

By mounting the engine outside, that is by fixing same to the outer surface of the frame, it is indeed possible to make the driving engine easily accessible and readily dismountable. In this case, however, it is necessary to use in the hitherto known individual axle drives, rather complicated transmission gears containing several pairs of toothed wheels, in order to enable the intermediate shaft between the steam engine and the gear to be mounted beside the driven wheels, whilst maintaining the required transmission ratio.

The present invention provides, in contradistinction to the known constructions, an improved arrangement of an individual axle drive, which embodies the feature of the required high speed of the engine and at the same time combines the features of perfect accessibility of the engine with the simplest possible construction of the force transmission between engine and driven axle. These advantages are attained by the employment of a particularly small driven wheel diameter, which, in the case of normal gauge locomotives, should be equal to the diameter of the

usual running wheels, therefore say between 1000 to 1300 mm. Driven wheels of this diameter will, at high speeds of travel, run with very high numbers of revolutions, and consequently the improved individual axle drive according to the invention will, in contradistinction to all known similar drives, lead for the first time to the possibility of attaining the required high speed of the driven engine, not by the employment of a considerable ratio of transmission of the usual toothed wheel transmission gear, but predominantly or even exclusively by the employment of a high number of revolutions of the driven axle itself. Apart from the above mentioned advantages, such a driven axle having particularly small driven wheels has the additional advantage of a minimum value of the non-sprung mass, which was hitherto quite unattainable. This feature is very valuable in connection with fast travelling locomotives owing to the resulting saving of the railway track.

Constructional examples of the invention are illustrated in the accompanying drawings.

Fig. 1 is an elevation of a locomotive having small driven wheels and individual drive of each axle by means of outwardly mounted steam engines and a simple toothed wheel transmission gear.

Figs. 2 to 4 are sections as follows:

Fig. 2 a cross section on line II—II, 30

Fig. 3 a section on line III—III, and

Fig. 4 a section on line IV—IV of Fig. 3,

Figs. 3 and 4 showing the cylinders 15 and 16 of the engine directed toward the front end of the locomotive.

Fig. 5 shows partly in cross section and partly in front view a second constructional form, in which the toothed wheel transmission gears are mounted outside and in front of the driven wheels.

Fig. 6 is a cross section partly in view corresponding to Fig. 5.

Fig. 7 is an elevation of a locomotive in which the driving steam engine operates the driven wheels directly without the use of any toothed wheel transmission gear.

Fig. 8 is a cross section on line VIII—VIII of Fig. 9.

Fig. 9 shows on a large scale the driving engine of an axle having two cylinders arranged in 50 V-formation, and the corresponding driven wheel.

Referring first to Fig. 1, it will be seen that the driven wheels 11 have the same diameter as the rear running wheels 12 of the locomotives. The driven wheels consequently have numbers 55

of revolutions which are so high that only a rather small toothed wheel transmission ratio is needed in order to obtain a very high number of revolutions of the steam engines, for instance 5 1000 to 1200 revolutions per minute at a travelling speed of the locomotive of about 175 km. per hour or about 110 miles per hour. All the details of the locomotives are diagrammatically shown in Figs. 2 to 4.

10 The driven axle 13 provided with driven wheels 11 of the reduced size, is driven by a steam engine 15, 16 fixed upon the frame 14, through a toothed wheel transmission gear 17, 18 and a resilient clutch 19. The steam engine consists in this 15 constructional example of two individual cylinders 15, 16, the cranks 20, 21 of which are displaced one with regard to the other through 90°. An essential feature of this construction is the mounting upon the outsides of the frame 14, 20 which is in usual manner sprung by means of springs 22 with regard to the driven axle 13, this mounting ensuring very perfect accessibility. The crank shaft 23 of the steam engine 15, 16 is carried past the driven wheels 11, to the toothed 25 wheel transmission gear 17, 18 arranged inside the frame, the casing 24 of the gear being likewise mounted upon the frame. The toothed wheel 18 is mounted upon a hollow shaft 25 mounted in a casing 24, said shaft carrying one 30 half 19 of the resilient clutch. This clutch is, in the construction shown, constructed as a spring cup clutch, the second half 26 of the clutch being fixed upon the driven axle 13. The force transmission between the clutch halves 19 and 26 is, in known manner, effected by springs 28 interposed between the two halves and mounted in casings 27.

35 The construction according to Figs. 1 to 4 having a transmission gear arranged inside the frame, is particularly suitable in all cases in which the driving engine consists of two units arranged one on each side of the locomotive, and provided with a common transmission gear.

On the other hand, the construction shown in 40 Figs. 5 and 6 is particularly suitable in cases in which each individual axle is driven from one side only, that is in which the steam engine appertaining to a driven axle is mounted as a self-contained unit at one side of the locomotive only. In such 45 constructions the engines of adjacent axles are alternately mounted upon the right and the left hand side of the locomotive. In the constructional example of Figs. 5 and 6, each steam engine appertaining to an axle 13 or 13' possesses 50 two cylinders 28, 29 arranged substantially in the same plane and inclined one with regard to the other by 90°, the connecting rods of the cylinders acting upon a common crank 34. One member of the crank is constructed as a toothed wheel 55 31, said wheel engaging with a second toothed wheel 32 mounted in front of the driven wheel 11. The crank shaft 34 and the shaft 36 of the toothed wheel 32 are mounted in a casing 35, which is fixed by means of the cylinders 28, 29 and lugs 30 to the frame 14. The transmission 60 of force from the shaft 36 to the wheel 11 again takes place by means of a resilient clutch constructed as a spring cup drives one half 33 of the clutch being mounted on the shaft 36, whilst the wheel 11 itself constitutes the other clutch half.

65 In this construction, not only the engine but also the toothed wheel transmission gear are mounted outside upon the frame in an easily accessible position. The small wheel diameter

again enables a single pair of toothed wheels to be used as the transmission gear, and the casing 35 is well mounted upon the frame 14.

70 In many cases the reduction of the diameter of the driven wheels forming an important feature of the invention, and the consequential increased number of revolutions of the axles, enable, even with a direct coupling of the engine with the driven axle, the dimensions of the driven engines to be kept sufficiently small. The total arrangement assumes then its simplest form, inasmuch as toothed wheel transmission can be entirely avoided. A constructional example of such an arrangement is shown in Figs. 7 to 9. The steam engine consists in this case each of 15 two cylinders 30, 31 mounted at an angle of about 90°, the connecting rods 32, 33 of the cylinders acting upon a common crank pin 34. This construction of the steam engine is particularly suitable for individual axle drive owing to the very 20 perfect balancing of the masses, and the very small width, that is, horizontal dimension, of the engine. The engines are fixed upon the outer sides of the frame 35 which is sprung with regard to the axles 38, and are consequently 25 easily accessible and readily exchangeable. The crank shaft 36 of each engine is, in this case, located in front of a driven wheel 37 and forms an extension of the driven axle 38. The resilient clutch is again constructed as a spring cup 30 drive, one half 39 of which is mounted upon the crank shaft 36 whilst the other half is constituted by the driven wheel 37 itself. The steam engines may obviously, in this case as well as in the constructional example of Figs. 1 to 4 be constructed in any other suitable manner, that is to say they may have different numbers of cylinders and different arrangements of the cylinders and so on, and they may for each individual axle be mounted at one side of the frame 35 only.

35 There are cases in which the limiting profile of the locomotive, does not permit of the crank shaft to be placed sufficiently low for directly driving the axles in accordance with Figs. 7-9, 45 even though the number of revolutions of the driven wheel is high enough to permit of such a drive being used. The resilient clutch 39 located between the crank shaft 36 and the wheel 37 does, to a certain extent, permit of the centre 50 of the crank shaft being placed slightly higher than the centre of the wheel. If, however, this displacement of the centre is not sufficient for the purpose, the employment of a simple toothed wheel transmission gear according to Figs. 1 to 55 6 must be resorted to, this gear, in such cases, having either no effective or only a very small transmission ratio and serving merely for the purpose of enabling the driving engine to be placed at a slightly higher level.

60 I claim:

65 In an individual axle drive for steam locomotives, the combination of: a frame; a plurality of driven axles carrying wheels of a diameter of 1000 to 1300 mm.; spring suspension means interposed between said frame and said driven axle; a plurality of completely enclosed independent steam-operated engines rigidly mounted outside upon said frame and having crank shafts coaxial with said driven wheels; resilient clutches interposed between said crank shafts and said driven axles, said engines each comprising two cylinders displaced through an angle of 90°.

70 HEINRICH CARL.
